Milton S. Braudall,
ATTORNEY

UNITED STATES PATENT OFFICE.

NELSON J. WARREN AND WILLARD C. SMITH, OF SIOUX CITY, IOWA.

OIL-VAPOR BURNER.

Application filed November 5, 1921. Serial No. 513,194.

To all whom it may concern:

Be it known that we, NELSON J. WARREN and WILLARD C. SMITH, citizens of the United States, and residents of Sioux City, 5 in the county of Woodbury and State of Iowa, have invented certain new and useful Improvements in Oil-Vapor Burners, of which the following is a specification.

Our present invention has for its object 10 the production of an improved gas burner.

Another object of the invention is the production of a gas burner particularly adapted for utilizing gas generated from liquid fuel.

15 A further object of the invention is the production of a gas burner embodying an improved controlling means.

Furthermore, the invention contemplates a gas burner having improved means for 20 both its cleaning and control.

The invention has for a further object the production of an improved oil vapor burner particularly adapted to be readily installed within a furnace.

25 With these and other objects in view, the invention, consisting in the construction, combination and novel arrangement of parts, will be fully understood from the following description, reference being had to 30 the accompanying drawing which forms a part of this application and which is a fragmentary, vertical section of the preferred form of the device as applied to a heater.

While we have illustrated but one form 35 of the invention, we would not be understood as being limited to such specific construction for various alterations and modifications may be made in the details of construction and arrangements of parts herein disclosed 40 without departing from the spirit and scope of the invention as defined in the appended claim.

The embodiment chosen for illustration is 45 particularly designed to be supported in any suitable manner within a furnace or other heater; a portion of the enclosure of which is represented by the furnace door, 1. The burner embodies a suitable supporting part for the burner proper which may be 50 provided by the generating pan, 2, above which is positioned a burner proper embodying a crescent-shaped duct having its arms, 3 and 4, upwardly extending, engaged, respectively, with the opposite sides of a retort receptacle, 5. The arm, 3, of the duct commu-

nicates with an induction passage, 6, depending through the pan, 2, and adapted to be connected with any suitable source of liquid fuel, which may be fed to the said passage, 6, either by gravity or pressure. At 60 the juncture of its arms, 3 and 4, the duct is provided with a transverse opening, 7, into which is threaded the body, 8, of the burner nozzle, having on its lower end a head, 9, adapted for engagement with the lower wall 65 of the duct or with a packing element, 10, interposed between the head, 9, and the wall of the duct. The body, 8, is provided with an axial bore, 11. Between the nozzle and the passage, 6, the arm, 3, of the duct is closed, as at 12, and within the duct the body, 8, is provided with an annular groove, 13, which permits gas from the duct arm, 4, to pass entirely around the nozzle body, 8, and into the nozzle through perforations, 14, in the grooved portion of the body. Into the upper end of the body, 8, is screwed the nozzle jet, 15, having a head, 16, adapted to be engaged with the end of the body, 8, or with the packing element, 17, interposed between 70 said head and body. The jet opening, 18, communicates with a counter bore, 19, on the interior of the jet, one end of the said counter bore adjacent the opening, 18, being 75 conical, as at 20, to serve as a guide for the throttle-wire, as will presently be made more clear.

The nozzle is positioned above the center of the pan, 2, and the head, 9, thereof is supported on an annular flange, 21, on the 90 bottom of the pan and around an opening, 22, in the bottom thereof. Extending through said opening, 22, is a short tube, 23, having its upper end threaded into the nozzle body head, 9. Into the lower end of the tube, 23, extends one end of a small tube, 24, preferably of semi-flexible material, as copper tubing, the lower end portion of said tube, 23, being provided with a counter bore, 25, to receive a gland nut, 26, to form a gas-tight connection between the tubes, 23 and 95 24. The tube, 24, is bent laterally and has its other end inserted in a tube, 27, and firmly secured therein by a gland nut, 28, screwed into a counter bore, 29, in the tube. The tube, 27, projects freely through an 100 opening, 30, in the heater enclosing part, 1, and is threaded into a plate, 31, as at 32, and is secured to said plate by a jam-nut, 33, 105 screwed onto the tube, 27, and into firm en- 110

gagement with the plate, 31, the latter being secured to the part, 1, by a bolt, 34, or otherwise.

The outer end portion of the tube, 27, is provided with a counter bore, 35, in which freely reciprocates a plunger, 36, encompassed by a gland nut, 37, screwed onto the tube, 27. To one end of the plunger, 36, is secured a wire, 38, which passes through the 10 guide tube, 24, and upwardly through the tube, 23, the nozzle body, 8, and into the nozzle jet, 15, the wire being of sufficient length that when the plunger is forced inwardly the wire will project through the jet opening, 18, 15 and movement of the plunger in the opposite direction withdraws the wire from the jet opening, 18, sufficiently to place the end of the wire within the counter bore, 19. The tapered end, 20, of the counter bore, 19, 20 serves to guide the wire into the jet opening, 18.

Now, it will be clear that liquid fuel entering the retort receptacle, 5, from the passages, 6 and 3, will be converted into gas by 25 the heat from the jet therebelow, and the gas is conveyed to the jet through the passage, 4, and nozzle body, 8. In this type of burner we do not burn the liquid fuel as is usual in liquid fuel burners, but rather 30 the oil is converted into vapor before being introduced into the nozzle, and, furthermore, we do not control the liquid fuel supply as is usual in liquid fuel burners to regulate the heat, but rather we control the 35 gas at the jet by extending and retracting the throttle-wire, 38, into and from the jet opening, 18, to accordingly decrease or increase the flow of gas from the jet.

The plunger, 36, is preferably controlled

by a lever, 39, fulcrumed at its center, as at 40 40 to a suitable bracket-arm, 41, on the plate, 31; and having a central depending arm, 42, connected by a toggle-link, 43, with the plunger, 36, whereby oscillation of the said lever, 39, will extend and retract the 45 throttle-wire. The opposite ends of the lever, 39, may be connected to the usual furnace draft controlling chains, 44, and if desired these may be automatically controlled by a thermostat.

Having thus described our invention, what we claim as new and desire to secure by Letters Patent of the United States, is:

An oil-vapor burner for a heater having an enclosing wall part, embodying a retort receptacle adapted to be positioned within the heater and receive oil from a source of supply, a nozzle below the receptacle including an upright hollow body, and a jet on the upper end thereof; a vapor passage between the receptacle and body, a supporting member projecting through the wall part of the heater, a tube having one end secured to the lower end of said body and the other to said supporting member, a throttle-wire 65 extending through the tube and into the body and adapted to be extended to or withdrawn from the jet opening to regulate the flow of vapor from the jet, and means for 70 extending or retracting the wire to any desired position, including a bracket arm adapted to be mounted on said wall part, a lever fulcrumed on the arm, and an operative connection between the lever and wire.

In testimony whereof, we have hereunto set our hands this 19th day of October, 1921.

NELSON J. WARREN.
WILLARD C. SMITH.
